UNITED STATES PATENT OFFICE

147,581

DESIGN FOR A COMBINATION CHAIR AND TABLE OR LIKE ARTICLE

Conrad R. Coulter, Kansas City, Mo.

Application May 3, 1946, Serial No. 129,287

Term of patent 7 years

(Cl. D15—6)

To all whom it may concern:

Be it known that I, Conrad R. Coulter, a citizen of the United States, residing at Kansas City, in the county of Jackson and State of Missouri, have invented a new, original, and ornamental Design for a Combination Chair and Table or Like Article, of which the following is the specification, reference being had to the accompanying drawing, forming part thereof.

Fig. 1 is a perspective view of a combination chair and table or like article showing my new design in a position for forming a chair.

Fig. 2 is a front elevational view.

Fig. 3 is a side elevation view.

Fig. 4 is a perspective view but showing the combination chair and table in a position for forming a table.

Fig. 5 is a perspective view showing a combination chair and table in inverted position for forming a rocking chair.

I claim:

The ornamental design for a combination chair and table or like article, substantially as shown.

CONRAD R. COULTER.
